UNITED STATES PATENT OFFICE.

JACOB KAISER, OF BROOKLINE, MASSACHUSETTS.

STEAM-ENGINE.

SPECIFICATION forming part of Letters Patent No. 285,904, dated October 2, 1883.

Application filed July 10, 1883. (No model.)

To all whom it may concern:

Be it known that I, JACOB KAISER, of Brookline, in the county of Norfolk, of the Commonwealth of Massachusetts, have invented a new and useful Improvement in Steam-Engines; and I do hereby declare the same to be described in the following specification and represented in the accompanying drawings, of which—

- 10 Figure 1 is a top view, Fig. 2 a horizontal section, and Fig. 3 a transverse section, of a steam-engine provided with my invention. Fig. 4 is a plan of the working-face of the valve D, hereinafter described. Figs. 5 and 15 6 are opposite side views of the valve D'. Fig. 7 is a view of the cylinder A' and the seat of the valve D' thereof. Fig. 8 is a side view of the cross-head M, for connecting the valves and their rod L, to be explained.
- 20 This engine has two cylinders and a single valve-chest therefor, arranged between them and containing two valves, applied to a single rod, operated by one eccentric and its valve-rod connection. The rods of the pistons of the 25 two cylinders have their cranks of the shaft to be driven arranged in planes at a right or an obtuse angle to each other, in order that each crank in passing a "dead-point" may be assisted by the force applied by the other 30 to revolve it.

In the drawings the two cylinders are shown at A and A', the intermediate valve-chest at B, the pistons at C and C', the slide-valves at D and D', and the valve-operating rod at L. 35 In one cylinder the piston thereof is exhibited as having completed its inward stroke, while in the other cylinder the piston is represented at half stroke.

The shaft E to be revolved has one crank, 40 F, arranged in a plane at a right angle relatively to that of the other, F', the connecting-rods of the two cranks and the piston-rod being shown at G and G'. The eccentric for operating the valve-rod is represented at I, and its 45 valve-rod connection at K.

The passages for leading steam to and from the cylinders are shown at a and a' and b and b', those for exhaust of the steam being represented at c and c' and d and d'.

50 The ports of the valve D are shown at e and

e', those of the valve D' being represented at f and f' and g and g', the last two being joined by a passage, g'. The two valves are connected with their rod L by a cross-head, M.

In Fig. 2 the steam-passage a of the cylinder A' is exhibited as uncovered by the valve, in which case steam from the chest B will flow through the said passage a into the cylinder, the exhaust-steam passing from the cylinder through the passage a', the port e', and the 60 passages c and c'. At the same time steam will be flowing through the port f' and the passage b' into the other cylinder, the exhaust-steam of which will be escaping by the passage b, port g, and the passages g', d, and d'. 65 On the piston C having completed its inward stroke, the piston C will be at half-stroke, and the cylinder A' will take steam through the port f and the passage b, and exhaust through the passage b', the port g', and the passages g', 70 d, and d'. On the piston C having completed its outward stroke, the cylinder A will receive steam through the passage a', and exhaust through the passage a, port e, and the passages c and c'. Each piston-crank, when at a dead-point, will be assisted past such by the other 75 piston and its crank.

An engine having two cylinders and their pistons and a single steam-chest arranged, as described, between and communicating 80 with the two cylinders by passages, as represented, and also having in the steam-chest two valves, like the valve C, and to be operated by suitable means, will be found of service, especially for locomotives for railways; 85 but when the crank of each cylinder is to be assisted in passing its dead-points it becomes necessary to have the cranks arranged in planes at an angle to each other, as described, and also to have to the two cylinders valves 90 and steam-passages therefor, essentially as shown in the drawings, and as hereinbefore explained.

I am aware that an engine has been provided with two cylinders having a steam-chest 95 between, in which are placed two valves having eccentric-rods, and also that a single valve has been used within such an intervening steam-chest.

What I claim is—

The combination of the two steam-engine cylinders A and A', their pistons C and C', and the connecting-rods G G' thereof, with the cranked shaft E, having its two cranks F F' arranged in planes at an angle to each other, and with the single steam-chest B, two slide-valves, D D', therein, the cross-head M, the

eccentric I, and its valve-rod connection K, all being substantially and to operate as set forth.

JACOB KAISER.
